ABSTRACT OF THE DISCLOSURE

Aromatic hydrocarbon compounds are selectively reduced electrochemically to their 1,4-dihydro derivatives in an ammoniated solvent-electrolyte system under conditions selected to effect oxidation of ammonia.

BACKGROUND OF THE INVENTION

Partial reduction of aromatic compounds to their respective 1,4-dihydro derivatives has been both difficult and expensive. Difficulty attaches both to the selective formation of dihydro derivatives and to the preparation of the 1,4-dihydro isomer to the substantial exclusion of the 1,2-isomer. Methods known in the art generally consume expensive reagents so that the cost of the desired product becomes prohibitively great.

Methods for reduction of an aromatic compound (A) to its 1,4-dihydro derivative (AH₂) can be represented stoichiometrically by the following equations:

Equation 1 represents direct catalytic hydrogenation, usually at elevated temperature and pressure. This method is impractical because of low yield and difficulty in adequately purifying the desired product.

Equation 2 represents the "Birch" sodium-alcohol synthesis and is characterized by high chemicals consumption and cost. The analogous lithium-amine synthesis is likewise expensive and yields dihydro derivatives only when an alcohol is added to the system.

Equation 3 is illustrative of the electrochemical reduction system recently reported by Misono et al. for benzene hydrocarbons in J. Electrochem. Soc., 115, 266 (1968) and in U.S. Pat. No. 3,485,726. This system was extended to naphthalene hydrocarbons as reported in Bull. Chem. Soc., Japan, 41, 2921 (1968). While selectivity of reduction to the 1,4-dihydro isomer is high, the process suffers limitations that render the cost too great for consideration when contemplating large-scale operation. Large inventories are required for both the tetraalkyl ammonium bromide electrolyte and the diethylene glycol dimethyl ether (diglyme) solvent. The electrolyte is consumed in the process (at the rate of 6 pounds per pound of dihydro naphthalene produced) as bromine is liberated. The separator required to isolate this bromine from the cathode has a high electrical resistance, greatly increasing power cost. Because the separator is not ideal, bromine diffusion must be reduced by keeping the concentration low. This requires a large volume of solvent in the anode chamber. Other solvents such as acetonitrile may be used but these are also expensive.

Electrochemical reduction of benzene and its derivatives employing an amine solvent and lithium halide electrolyte has been reported by Benkeser et al. in J. Am. Chem. Soc., 86, 5272 (1964). An undivided cell was required for preparation of 1,4-dihydro isomers. In a divided cell lithium amide was formed in the reaction and catalyzed isomerization to the conjugated 1,2-dihydro form

2

which was readily reduced further. Solvent was oxidized to condensation products.

More recently, electrochemical reduction of benzene to 1,4-dihydrobenzene has been effected employing an alkali halide and an alcohol in liquid ammonia (U.S. Pat. No. 3,493,477) or a lithium halide and an alcohol in hexamethyl phosphoramide (U.S. Pat. No. 3,492,207). The former requires rigorous exclusion of iron and water, operates at very low temperature or high pressure and provides a low current efficiency. The latter operates with a cell divider and exhibits a satisfactory current efficiency but at low conversion levels.

SUMMARY OF THE INVENTION

This invention relates to an improved process for electrochemical reduction of aromatic compounds selectively to the corresponding 1,4-dihydro derivatives.

Specifically, this invention relates to an electrochemical reduction process for aromatic compounds employing ammonia as the anode depolarizer, under conditions selected to yield dihydro aromatic derivatives, as the 1,4- or non-conjugated isomer, at the cathode while liberating nitrogen gas at the anode.

One object of this invention is the production of 1,4-dihydro naphthalenes by electrochemical reduction of a selected naphthalenic hydrocarbon, employing oxidation of ammonia as the effective source of the required electrons.

A particular object of this invention is to provide an economically attractive method for conversion of naphthalene to 1,4-dihydro naphthalene, employing electro-reduction in an ammoniated solvent-electrolyte system.

Other objects of our invention will become apparent as the invention is further described.

DESCRIPTION OF THE INVENTION

Our invention effects the partial, selective reduction of aromatic compounds to 1,4-dihydro aromatic compounds in an electro-chemical cell containing the aromatic hydrocarbon dissolved in a solvent-electrolyte and operating at a current density (and cathode potential) insufficient to effect evolution of much hydrogen. Ammonia is added to the solution in an amount at least equal to and preferably in excess of that stoichiometrically required for service as a proton donor (or replenisher), whereby the ammonia is oxidized electrochemically and molecular nitrogen is formed. The solvent-electrolyte system comprises an aprotic solvent together with minor quantities of water and a salt soluble therein, preferably a quaternary ammonium halide. Electrolysis is continued until substantially all of the aromatic compound has been reduced. After separation from the solvent components the dihydro aromatic product is separated by conventional means, such as distillation, from minor amounts of aromatic compound and more highly reduced derivatives. The 1,4-dihydro aromatic can be purified by distillation because of the absence of the close-boiling 1,2-dihydro isomer. Very little electrolyte is consumed. Accordingly, chemicals consumption is limited to substantially a stoichiometric quantity of ammonia which is both inexpensive and readily available in pure form.

In our electrochemical process the reactions can be represented as:

Operating and economic advantages for this process include the need for only a small inventory of quaternary ammonium salt and of solvent. This greatly lowers chemicals cost and plant size. No separator is required in the

electrolytic cell and this greatly reduces electric power consumption while simplifying plant construction.

Suitable aromatic compounds for the practice of this invention include aromatic hydrocarbons, their alkyl and cycloalkyl derivatives, and substituted aromatic hydrocarbons having polar substituents such as carboxyl, cyano, halo, and like groups. Examples of such compounds include alpha-methylnaphthalene, beta-methyl-naphthalene, binaphthyl, benzoic acid, phthalic acid, terephthalic acid, isophthalic acid and naphthoic acids. Especially suitable compounds include naphthalene and benzo-substituted naphthalenes such as triphenylene (1,2,3,4-dibenzonaphthalene).

Aromatic hydrocarbons such as naphthalene and the methylnaphthalenes are readily obtained in substantially pure form by distillation from petroleum reformer bottoms (by-product from aromatic gasoline manufacturing processes such as Ultraforming) or from coke-oven distillate.

Suitable aprotic solvents include acetonitrile, dimethylformamide, dimethyl sulfoxide, alkyl ethers, glycol ethers, and especially alkylene glycol alkyl ethers. These are characterized by their lack of proton donor capacity. We particularly prefer to employ diethylene glycol dimethyl ether, generally known as "diglyme," because of its solvent power for both aromatic hydrocarbons and polar compounds.

Our electrochemical process requires the presence of a small quantity of water (see the equations above), which is continuously regenerated, and also an electrolyte salt which must be soluble in the combination of water and aprotic solvent. For this purpose we prefer to use tetraalkyl ammonium halides. Both chlorides and bromides are satisfactory. The alkyl substituent is preferably a butyl group. With propyl groups solubility of the salt is borderline while pentyl groups may not be sufficiently stable. We particularly prefer to use tetrabutyl ammonium bromide.

When preparing the electrolysis solution the concentrations of the various components can be varied within rather wide limits. An effective electrolysis medium will be obtained when the respective components of the solution are employed in the following concentration ranges:

	Wt. percent
Diglyme	50-80
Water	3-10
Tetrabutyl ammonium bromide	2-25
Naphthalene	10-30

Care should be taken to maintain a one-phase liquid medium so that, for example, the maxima indicated above for water, salt, and naphthalene will not be present simultaneously. When preparing 1,4-dihydronaphthalene, we prefer to use solutions containing 15 to 25 wt. percent naphthalene, 5 to 10 wt. percent tetrabutyl ammonium bromide salt and 3 to 5 wt. percent water together with diglyme.

Ammonia is consumed in our process and accordingly should always be present in some excess concentration over that stoichiometrically required for the electro-reduction. A high concentration of ammonia need not be employed, but it has been found convenient to maintain the solvent-electrolyte system about 1 molar in ammonia. This can be maintained approximately by continuously bubbling ammonia into the solution contained in the electrolysis cell during reduction. If the solution is continuously removed from the cell for cycling through a cooling system, ammonia can be conveniently injected into the line, preferably downstream of the pumping means.

In the practice of our invention carbon anodes have been satisfactory. The carbon may be impregnated with a metal; e.g. platinum, although metals tend to oxidize and then plate out on the cathode. The cathode must be a material exhibiting a high hydrogen overvoltage such as lead, mercury, aluminum, tin, zinc and cadmium. Lead and mercury are especially suitable.

In our preferred system ammonia is the most easily oxidized entity so that oxidation of bromide ion is essentially eliminated. The operating voltage should avoid electrolysis of water and consequent liberation of hydrogen. In general, an impressed potential in the range from about 5 to about 25 volts, and preferably from 6 to 15 volts, may be employed. Current density will accordingly vary within the range from 20 to 50, and desirably 20 to 35, amperes per square foot.

Electrolysis temperature is not a critical variable and reductions may readily be conducted within the range from 70° to 140° F. The solvent-electrolyte solution must be fluid at the selected temperature and the solubility of ammonia must be adequate to satisfy stoichiometric requirements. Operation at or near room temperature (80° to 120° F.) is preferred. During electrolysis part of the solution may be continuously removed from the cell, passed through a cooling coil, injected with ammonia, and returned to the cell.

As our selective electro-reduction progresses, the impressed voltage is increased to maintain the desired current density whenever there is a slow erosion of the carbon anode (for example, a loss amounting to about 0.001 inch per 24 hours). Salt consumption is low, although it tends to increase at low water concentrations while hydrogen evolution occurs at high water concentrations. No separator is required in our system. Indeed, presence of a separator to afford compartments and minimize mixing between reagents could lead to an inoperable system by effecting precipitation of, for example, ammonium bromide on the separator frit, and thus gradually shut off the electrochemical reaction.

When the reduction operation is complete the cell contents are usually transferred to a still and heated under mild vacuum to remove solvent, water and ammonia. The still bottom is extracted with a light aliphatic solvent (e.g., hexane). Tetraalkyl ammonium halide is recovered from the residue and a crude hydro-aromatic product is recovered from the extract. If susceptible to distillation this crude product is readily resolved into fractions containing tetra-hydro, di-hydro and unreacted aromatic compounds. The di-hydro fraction is free of the 1,2-dihydro isomer so that conventional distillation or extractive distillation can afford the desired 1,4-dihydro isomer in high purity.

In continuous operation, our process comprises the use of banks of electrolytic cells, each bank including a plurality of cells arranged in a line and having abutting walls to conserve space. Each cell is relatively narrow and deep and fitted with thin, flat facing electrodes disposed vertically. In one such arrangement each anode (carbon) and each cathode (any conductor having a high hydrogen overvoltage and preferably lead) is punched in the center and supported from a hollow rod extending upwardly. Either or both rods may be adapted to adjust horizontally the spacing between the electrodes to any desired distance. Inlet and exit lines are provided for flow of solution through the cell. Ammonia is added continuously to each cell through the hollow support rods or alternatively is injected into the inlet lines.

Within a cell-bank the electrical connections to the electrodes are arranged in series. Between cell-banks electrical connections may be either in series or in parallel arrangement. The solution flow pattern may be arranged in parallel within a cell-bank and in series between a plurality of banks as required to give substantially complete reduction to the 1,4-dihydro stage. Provision can be made for cooling the solution outside the cells as needed. Solution may also be recycled, in whole or in part, as required to effect a conversion of at least 80%. When recovering product, as by distillation or extractive distillation, part of the 1,4-dihydro product may be removed in a bottom stream together with the less volatile feed material and recycled therewith to an appropriate cell-bank.

The 1,4-dihydro aromatic compounds are highly desirable because they are capable of undergoing the known

reactions of olefinic systems inasmuch as they are non-conjugated olefins. They are capable of undergoing polymerization, formation of glycols and halohydrins and oxidation to polybasic acids. One reported use for 1,4-dihydro naphthalene (Chem. Eng. News 47, No. 45, 46 [1969]) is in modifying diene polymerizations to afford special properties in synthetic rubbers.

EMBODIMENTS OF THE INVENTION

The following embodiments are presented as illustrative of our invention and are not to be construed as limitations upon its reasonable scope.

EXAMPLE I

An electrolytic cell was fitted with a flat, circular carbon anode (1.5-inch diameter, $\frac{1}{8}$ inch thick) disposed horizontally and supported above a pool of mercury in the bottom of the cell, serving as a cathode. The carbon anode was platinized to the extent of 20 mg./cm.² surface. A sparger tube was inserted in the cell and a coated stirring bar was floated on the mercury. Lead wires connected the electrodes to a power source. The cell was filled with 10 grams of a solution containing 20 wt. percent naphthalene, 7 wt. percent tetrabutyl ammonium bromide, 7 wt. percent water and the remainder diethylene glycol dimethyl ether (diglyme). A potential of 23 volts was impressed across the electrodes while ammonia was bubbled into the cell through the sparger tube. The current density was 40 amperes/square foot. After the reaction was stopped, crude product was recovered by distillation to remove solvent and extraction with n-hexane to remove electrolyte. The crude product was analyzed and contained 1 wt. percent naphthalene, 6 wt. percent Tetralin, and 93 wt. percent 1,4-dihydronaphthalene. Current efficiency was 70%.

EXAMPLE II

Example I is modified employing tetrabutyl ammonium chloride as the electrolyte salt. Selectivity is unchanged and current efficiency is somewhat less.

EXAMPLE III

Two percent triphenylene was dissolved in a solvent (90 parts diglyme and 10 parts water) containing 25 wt. percent tetra-n-butyl ammonium bromide. Electrolysis was conducted using a carbon anode and mercury cathode at a current density of 30 amperes/square foot. The sole product was 1,4-dihydro triphenylene (1,4-dihydro 5,6,7,8-dibenzo-naphthalene).

EXAMPLE IV

Two percent triphenylene is dissolved in a solvent (95 parts diglyme and 5 parts water) containing 25 wt. percent tetra-n-butyl ammonium bromide. Ammonia is bubbled in continuously. Electrolysis is conducted as in Example III and the same product is obtained.

EXAMPLE V

An electrolytic cell was fitted with disc electrodes 9 inches in diameter and $\frac{1}{4}$ inch thick. A carbon anode was disposed horizontally near the bottom of the cell. A lead cathode was punched out at its center to receive a hollow cylindrical support rod and was maintained parallel to and above the anode by insulating spacers placed therebetween. The separation between the electrodes was 0.03 inch. A suction tube was extended from the cell to a circulating pump. The effluent line from the pump then was passed through a cooling bath and adapted to returning to the cell through the hollow support rod. Ammonia was injected continuously through a T in the effluent line downstream from the cooling coil. Sheathed lead wires connected the electrodes to a power source. A voltmeter and an ammeter were provided in the circuit. The cell was filled with a solution containing 20 wt. percent naphthalene, 4 wt. percent water, 7 wt. percent tetrabutyl ammonium bromide and 69 wt. percent diglyme. Ammonia

was then added to provide an approximately 1 molar concentration. While circulating the solution and continuously injecting ammonia, a potential of 8 volts was impressed across the electrodes. The current density was 33 amperes/square foot. Crude product was recovered and distilled to yield 3 wt. percent naphthalene, 7 wt. percent Tetralin and 90 wt. percent 1,4-dihydronaphthalene. Current efficiency was 60%.

EXAMPLE VI

The apparatus of Example V was employed in a 455-hour run, conducted in seven batch operations of 65 hours each. Electrodes were not cleaned or moved between batches. Each batch employed 8 kg. solution containing 20 wt. percent naphthalene, 4 wt. percent water, 7 wt. percent tetrabutyl ammonium bromide, 69 wt. percent diglyme and ammonia to provide 1 molar concentration. Solution was pumped (with ammonia injection) to maintain a temperature of 100° F. and to provide a velocity of 3 feet/second in the space between the electrodes. A potential of 8 volts was used at the start of the run to provide a current density of 33 amperes/square foot. During the final batch operation the potential had been increased to 14 volts. After 455 hours operation the spacing between electrodes had increased to 0.06 inch and there was a coating on the cathode. Current efficiency was nearly constant, being 63% for the first batch and 65% for the last batch. Crude product from the combined batches was recovered by distillation and hexane extraction of the still bottoms. The crude material (9.55 kg.) contained 3 wt. percent unreacted naphthalene, 7 wt. percent Tetralin and 90 wt. percent 1,4-dihydro naphthalene.

EXAMPLE VII

Example VI is modified by increasing the water content of the solution to 4.5 wt. percent. The initial potential is 6 volts to provide a current density of 20 amperes/square foot. In the final batch the potential has increased to 8 volts. The yield selectivity (to 1,4-dihydro naphthalene) is 93% and the current efficiency is 65%.

We claim:

1. A process for the production of a 1,4-dihydro aromatic hydrocarbon compound comprising electrochemically reducing, at a cathode, an aromatic hydrocarbon compound contained in an organic solvent-electrolyte system, introducing substantially anhydrous ammonia into the solution and concurrently oxidizing said ammonia at an anode.
2. The process of claim 1 wherein the aromatic hydrocarbon compound is a condensed-ring aromatic hydrocarbon selected from the class consisting of naphthalene, alkyl-substituted naphthalenes, and benzo-substituted naphthalenes.
3. The process of claim 1 wherein the organic solvent-electrolyte system comprises a major amount of an aprotic organic liquid together with about 3 to 10 wt. percent water and about 2 to 25 wt. percent of a tetraalkyl-substituted ammonium halide, wherein the alkyl substituents contain at least four carbon atoms and the halide is bromide or chloride.
4. The process of claim 3 wherein the aprotic organic liquid is a dialkylene glycol dialkyl ether.
5. The process of claim 1 wherein ammonia is maintained in solution in the organic solvent-electrolyte system in an amount in excess of that required for the anodic oxidation.
6. A process for the electrochemical production of a 1,4-dihydro aromatic compound, comprising the steps of:
  - (a) dissolving an aromatic compound in an organic solvent-electrolyte system comprising a dialkylene glycol dialkyl ether together with 3 to 10 wt. percent of water and 2 to 25 wt. percent of a tetrabutyl ammonium halide, selected from the class consisting of chloride and bromide;
  - (b) introducing the solution into an electro-chemical

- cell having a metallic cathode and a carbon anode spaced therefrom;
- (c) introducing substantially anhydrous ammonia into the solution;
- (d) imposing a potential of at least 5 volts between the anode and the cathode;
- (e) conducting electrolysis, with oxidation of ammonia and evolution of nitrogen gas at the anode, until a major portion of the aromatic compound has been reduced;
- (f) withdrawing the solution from the cell; and
- (g) separating the 1,4-dihydro aromatic compound from the other components of the solution.

7. The process of claim 6 wherein the dialkyleneglycol dialkyl ether is diethylene glycol dimethyl ether.

8. The process of claim 6 wherein the ammonium halide is tetrabutyl ammonium bromide.

9. The process of claim 6 wherein the organic solvent-electrolyte system contains 3 to 10 wt. percent water and 2 to 25 wt. percent tetrabutyl ammonium bromide dissolved in diethylene glycol dimethyl ether.

10. The process of claim 6 wherein solution contains 10 to 30 wt. percent aromatic compound and is maintained at a temperature in the range from 70° to 140° F.

11. The process of claim 6 wherein the cathode metal is mercury or lead.

12. The process of claim 6 wherein ammonia gas is continuously bubbled into the solution by means of a sparger located in the cell.

13. The process of claim 6 wherein a portion of the solution is cycled continuously by pumping from the cell through an external pipe and ammonia is introduced continuously into the solution prior to returning to the cell.

14. The process of claim 6 wherein the imposed potential is in the range from 5 to 25 volts.

15. The process of claim 6 wherein the current density is in the range from 20 to 50 amperes per square foot.

16. The process of claim 6 wherein the aromatic compound is naphthalene and the product is 1,4-dihydro naphthalene.

17. The process of claim 6 wherein the aromatic compound is triphenylene and the product is 1,4-dihydro triphenylene.

18. A process for the electrochemical production of 1,4-dihydro naphthalene, substantially free of the 1,2-isomer, comprising the steps of:

- (a) dissolving naphthalene in an electrolyte-solvent system comprising diethylene glycol dimethyl ether together with minor amounts of water and tetrabutyl ammonium bromide, to yield a solution comprising 15 to 25 wt. percent naphthalene, 3 to 5 wt. percent water, 5 to 10 wt. percent tetrabutyl ammonium bromide, and 77 to 60 wt. percent diethylene glycol dimethyl ether;
- (b) introducing the solution into an electrolytic cell, fitted with flat, horizontal carbon anode and a flat lead cathode, disposed about 1 millimeter above the anode and supported on a hollow, cylindrical rod;
- (c) adding ammonia to the solution, to maintain about 1 molar concentration of ammonia, by continuously circulating the solution from the cell through an external ammonia injection system and returning the ammoniated solution to the cell through the hollow cathode support rod;
- (d) maintaining the cell at a temperature in the range from 80° to 120° F. while impressing a potential in the range from 6 to 15 volts across the electrodes, to provide a current density in the range from 20 to 35 amperes per square foot;

- (e) continuing the electrolysis until at least 80% of the naphthalene has been converted; and
- (f) separating the 1,4-dihydro naphthalene from the resultant solution.

19. A continuous process for the electrochemical production of 1,4-dihydro naphthalenic hydrocarbons, substantially free of the respective 1,2-isomers, comprising the steps of:

- (a) dissolving a naphthalenic hydrocarbon feedstock in a solvent-electrolyte system comprising diethylene glycol dimethyl ether together with minor amounts of water and tetrabutyl ammonium bromide, to yield a solution comprising 15 to 25 wt. percent naphthalenic hydrocarbon, 3 to 5 wt. percent water, 5 to 10 wt. percent tetrabutyl ammonium bromide, and 77 to 60 wt. percent diethylene glycol dimethyl ether;
- (b) flowing the solution through electrolytic cells arranged in a plurality of cell-banks, each cell being fitted with a thin, flat, vertical carbon anode and a thin, flat, vertical, electrically conducting cathode, having a high hydrogen overvoltage, spaced from the anode;
- (c) adding ammonia to the solution prior to flowing through the cells, to maintain about 1 molar concentration of ammonia;
- (d) maintaining the cells at a temperature in the range from 80° to 120° F. while impressing a potential in the range from 5 to 25 volts across the cell electrodes, to provide a current density in the range from 20 to 50 amperes per square foot;
- (e) conducting the electrolysis until at least 80% of the naphthalenic hydrocarbon has been converted; and
- (f) separating the 1,4-dihydro naphthalenic hydrocarbon from the product solution.

20. The process of claim 19 wherein the naphthalenic hydrocarbon is naphthalene and the product is 1,4-dihydro naphthalene.

21. The process of claim 19 wherein the electrolytic cells within a cell-bank are connected electrically in series.

22. The process of claim 19 wherein parallel solution flow is maintained through each cell-bank and series solution flow is maintained between adjacent cell-banks.

23. The process of claim 19 wherein the anode position within each cell is fixed and the cathode is adjustably positioned horizontally in relation thereto.

24. The process of claim 19 wherein at least a portion of the effluent solution from the last cell-bank is continuously removed from the process system, the remaining solution being returned to the system for processing through at least one cell-bank.

25. The process of claim 19 wherein the 1,4-dihydro naphthalenic hydrocarbon is purified by extractive distillation and a portion of the 1,4-dihydro naphthalenic hydrocarbon is recovered in a bottom stream together with unconverted feedstock and recycled through at least one cell-bank.

26. The process of claim 19 wherein the cathode is lead.
